CLAIM

The ornamental design for footwear, as shown and described.

DESCRIPTION

FIG. 1 is a perspective view of the footwear in a folded configuration, showing my new design;

FIG. 2 is a perspective view of the footwear in an extended configuration;

FIG. 3 is a front view of the footwear in a folded configuration;

FIG. 4 is a front view of the footwear in an extended configuration;

FIG. 5 is a back view of the footwear in a folded configuration;

FIG. 6 is a back view of the footwear in an extended configuration;

FIG. 7 is a first side view of the footwear in a folded configuration;

FIG. 8 is a first side view of the footwear in an extended configuration;

FIG. 9 is a second side view of the footwear in a folded configuration;

FIG. 10 is a second side view of the footwear in an extended configuration;

FIG. 11 is a top view of the footwear in a folded configuration; and,

FIG. 12 is a top view of the footwear in an extended configuration.

Any broken lines that may be used to show an environment are for illustrative purposes only and form no part of the claimed design.
